P. R. GLASS

BEATING MACHINE

Filed Nov. 1, 1919

Fig. 1.

Fig. 2.

Patent Glass

UNITED STATES PATENT OFFICE.

PERLEY R. GLASS, OF WAYLAND, MASSACHUSETTS, ASSIGNOR TO UNITED SHOE MACHINERY CORPORATION, OF PATERSON, NEW JERSEY, A CORPORATION OF NEW JERSEY.

BEATING MACHINE.

Application filed November 1, 1919. Serial No. 335,201.

To all whom it may concern:

Be it known that I, PERLEY R. GLASS, a citizen of the United States, residing in Wayland, in the county of Middlesex and State of Massachusetts, have invented certain Improvements in Beating Machines, of which the following description, in connection with the accompanying drawings, is a specification, like reference characters on the drawings indicating like parts in the several figures.

This invention relates to the finishing of boots and shoes and more particularly to the covering of heels, which have been already attached thereto, with flexible material such as leather or fabric.

It has been proposed to cover heels of leather or leather substitutes, after they have been attached to women's shoes, by suitable coverings cut approximately to shape and treated with an adhesive before their application to the heels. After a covering has been applied to a heel it is trimmed so as to leave a narrow projecting edge around the top, which is then tucked into the rand crease. It is, when heels are so covered, desirable to smooth the portion of the heel cover adjacent to the rand crease and to shape up the covered heel in such a form as will leave a comparatively sharp edge, close up to the counter portion of the upper, as distinguished from a rounded edge with the resulting open and wide rand crease.

An object of my invention is to provide a simple machine well adapted to treat a freshly applied covering on a heel which has been prepared according to the foregoing process to smooth up the portion of the covering adjacent to the shoe upper. This I may accomplish by the provision of a suitably shaped beating tool reciprocated in a guideway which, preferably, is adjustable.

A feature of my invention is the provision in such a machine of means which may be used as a guide to facilitate the presentation of the heel thereto and to protect the upper of the shoe from defacement by the accidental action of the machine thereon.

These and other features of the invention, including certain details of construction and combinations of parts will now be described with reference to the accompanying draw-

ings, which show, for illustrative purposes, a preferred embodiment of my invention, 55 and pointed out in the claims.

Fig. 1 is a perspective view of the machine, somewhat broken away to better disclose the invention; and

Fig. 2 is a section on line 2—2 of Fig. 1. 60

The machine of the drawing is provided with a main frame 10 in which is mounted a drive shaft 12 rotated from a suitable source of power through tight and loose pulleys 14. This shaft is provided with an eccentric 16 65 and with a reduced portion 18 extending beyond the eccentric and concentric with the main portion of the shaft. Operated by the eccentric and provided with a pair of parallel jaws 20 engaging the same is a pounding or beating tool 22. To limit the movement of the beating tool to the desired path and to guide the reciprocation thereof there is provided a guideway or housing 24 adjustably connected as by a screw and slot connection 26 to a support 28 rigidly connected to the main frame. 70

Attached to the front of the guideway and forming a part thereof is a plate 30 tapered at its lower end to form, in effect, a 80 flange projecting slightly beyond the extremity of the guideway and adapted to enter the rand crease of a shoe held in the hand of the operative and pressed thereby against the pounding tool. To assist in the 85 guiding of the operating tool the latter is provided with a slot 32 engaging the reduced portion 18 of the shaft. To cover and protect the upper portion of the reciprocating tool and the eccentric 26 there is preferably 90 provided the housing 34 having an extension 36 directed towards the guideway 24.

In the operation of the machine, shoes to which heel coverings have been freshly applied are held in the hands of the operative 95 and presented thereby to the reciprocating tool in the manner indicated in Fig. 2. The tapered edge of plate 30 forms a narrow guide shaped to enter the rand crease and facilitates the guiding of the shoe as the 100 latter is rotated to bring the various parts of the upper portion of the heel covering into operative relation to the tool. By means of this guide the effect of the tool is easily limited to the desired portion of 105 the heel covering and any inadvertent oper-

ation of the tool on the upper of the shoe with a possible defacement thereby is avoided.

Having described my invention, what I claim as new and desire to secure by Letters Patent of the United States is:

1. A machine of the class described having, in combination, a reciprocating tool, a guide adjacent thereto, and means for reciprocating said tool comprising a rotatable shaft, an eccentric thereon, and a concentric portion of said shaft of a reduced diameter beyond said eccentric, said tool comprising a jaw to embrace the eccentric, and a slot 15 adapted to be seated over said reduced portion of the shaft to secure rectilinear movement of the tool.

2. A heel smoothing machine having, in combination, a hammer for beating the lateral surface of the heel of a shoe, means for pounding said hammer against the surface to be beaten, and shoe guiding means constructed and arranged to enter the rand crease of the shoe and protect the upper 25 from the action of the hammer.

3. A heel smoothing machine having, in combination, a hammer for beating the lateral surface of the heel of a shoe, a rigid

rest on opposite sides of said hammer, and a fixed rand crease entering guide on a third side of said hammer.

4. A heel smoothing machine having, in combination, a hammer for beating the lateral surface of the heel of a shoe, a rest on three sides of said hammer, and a fixed 35 rand crease entering guide on a fourth side of said hammer.

5. A machine of the class described having, in combination, a tool, a housing surrounding and slidably guiding said tool and arranged to guard against undesired contact therewith, and a flange on an edge of said housing adjacent to the operating surface 40 of said tool.

6. A machine of the class described having, in combination, a main frame, a guideway mounted thereon and arranged for adjustment with respect thereto, a shoe-beating hammer movable in said guideway, means for pounding said hammer, and a 45 rand crease entering guide rigidly supported on said guideway to facilitate the presentation of a shoe to said hammer.

In testimony whereof I have signed my name to this specification.

PERLEY R. GLASS.
